UNITED STATES PATENT OFFICE.

GEORGE H. WOMELSDORF, OF PHILADELPHIA, PENNSYLVANIA.

MACHINE FOR MAKING PAPER TUBES.

Application filed December 19, 1919. Serial No. 346,026.

To all whom it may concern:

Be it known that I, GEORGE H. WOMELSDORF, a citizen of the United States, residing in Philadelphia, Pennsylvania, have invented Machines for Making Paper Tubes, of which the following is a specification.

One object of my invention is to provide a relatively simple, compact and substantial device for rolling up a previously formed length of sheet material to form a frusto-conical tube which may serve as the body of a container; the invention more particularly contemplating novel means for automatically feeding and guiding the strip around a mandrel and for retaining it thereon during the winding operation.

My invention further contemplates novel mechanism for insuring the entrance of a length of strip material between a pair of winding rolls and thereafter so actuating said rolls as to cause them to grip the material, together with a mandrel of novel construction for holding the strip in place during the first part of the winding operation.

I also desire to provide novel means for trimming the ends of a rolled up body of sheet material, particularly when such body has a frusto-conical form, together with novel means for preventing the entrance between the feeding rolls of a second length of strip material as long as a previously delivered length of such material or the tubular body formed therefrom, remains upon the mandrel.

Another object of my invention is to provide a machine having coacting tapered rolls mounted in such a manner as to cause a curved length of sheet material to be gripped and with the aid of suitable guiding means, to be formed into a frusto-conical tube.

These objects and other advantageous ends I attain as hereinafter set forth, reference being had to the accompanying drawings, in which,

Figs. 1 and 2 are respectively a side and a front elevation of a machine constructed in accordance with my invention;

Fig. 3 is a plan of the machine shown in Figs. 1 and 2;

Fig. 4 is a longitudinal section on a larger scale than Figs. 1 to 3 inclusive, illustrating the detail construction of the winding roll or mandrel;

Fig. 5 is a plan on a reduced scale, illustrating the form of blank strips which the machine is designed to operate upon; and

Fig. 6 is a perspective view of the finished tube or container body made by my machine.

In the above drawings 1 represents a supporting base to which is suitably fixed a frame 2 providing a pair of bearings 3—3 for the reception of a shaft 5 to which is fixed a driving pulley 7 and a bevelled gear 8. Said frame also includes a fixed extension 4, above one of the bearings 3 having a guideway for a bearing 16 in which is rotatably mounted one end of a second shaft 6. The opposite end of this shaft which extends above and at an acute angle to the shaft 5, is supported in a second bearing 13 vertically slidable in a guideway provided in a lever 12 fulcrumed by a pin 13^a to a pair of lugs constituting part of the frame 2.

Two springs, of which one is shown at 14, are mounted between the bearings 16 and 13 and the upper ends of their respective guideways, and adjusting screws 15 and 17 are provided for varying the pressure exerted by said springs upon their respective bearings. The shaft 10 on the outer side of its bearing 13 has fixed to it a frusto-conical roll 10 designed to cooperate with a second frusto-conical or tapered roll 11, fixed to the adjacent end of the shaft 5, which has fixed to it a bevelled gear 8 meshing with a second bevelled gear 9 fixed to the shaft 6.

The lever 12 is extended on that side of the roll 10 opposite its fulcrum 13^a and has its free end pivoted at 19 to a toggle lever 18, one of whose arms is pivoted at 20 to the lower end of a link 21 whose upper end is pivoted at 22 to a standard 23 projecting upwardly from the base 1. The second arm of the toggle lever 18 is provided with a roller 24 designed to cooperate with a cam 25 fixed to a cam shaft 26 and this is driven from the shaft 6 through a sprocket chain 27 and suitable sprocket wheels.

A strip-supporting feed table 28 is carried by the frame 2 on one side and at the level of the top of the roller 11, on whose opposite side is mounted a guide 29 for directing a strip of material *w* down around said roll after it has passed between it and

the roll 10. This strip guide includes a relatively sharp edge 30 parallel with and immediately adjacent the nearest portions of the two rolls 10 and 11 and carries a series of 5 frusto-conical pressure rolls 31 positioned to engage the strip or tube on the roll 11 when this is desirable.

The guide structure 29 is mounted on one end of a tubular member 32 slidable in a 10 guideway 33 and designed for the reception of one end of a plunger 34 whose opposite end carries a roller 35 cooperating with a cam 36 on the shaft 26, there being a spring 37 within the member 32 acted on by the 15 plunger 34. With this construction the strip guide 29 under certain conditions is yieldingly pressed toward the roll or mandrel 11 so that its rollers 31 forcibly press upon the surface of a strip being wound on 20 said mandrel.

Immediately under the table 28 is mounted an adhesive container 40 having within it a roll 41 constantly immersed to a greater or less extent in the adhesive and engaging the 25 surface of a second roll 42 mounted on a pair of arms 43 pivoted coaxially with the first roll 41;—the arrangement being such that the roll 42 may be moved into and out of engagement with the strip being wound 30 upon the mandrel 11.

For actuating the swinging arms 43 and moving the roll 42 into and out of operative position, I provide a lever 44 pivoted to a suitable supporting standard 45 and having 35 one end connected to said arms 43 while its second end carries a roller 46 cooperating with a cam 47 on the cam shaft 26;—the arrangement being such that said lever is periodically swung on its fulcrum to accomplish the result desired.

In order to trim the ends of a tube wound on the mandrel 11, I provide a forked lever 48 fulcrumed on a standard 48^a and having journaled in its branches two short spindles 49 and 50 respectively having fixed to them rotary cutters 51 and 52 so positioned as to cooperate with the mandrel 11 adjacent the ends thereof, in cutting or trimming the tube wound thereon. The spindle 49 for the cutter 51 is operatively connected to the spindle 50 through an intermediate spindle 53 and two universal joints, and said spindle 50 is driven from the shaft 5 through a pair of coacting gear wheels 54 and 55.

55 That end of the lever 48 distant from that supporting the cutters carries a roller 56 placed to cooperate with a cam 57 on the cam shaft 26, so that at certain predetermined intervals said lever is turned on its fulcrum and its cutters 51 and 52 are caused to operate on the material wound upon the mandrel 11.

For preventing material being fed between the rollers 10 and 11 when these 60 already have upon them a tube of material

or are in process of operating upon a previously fed strip, I provide a stop in the form of a finger 60 normally projecting across the table 28 to a greater or less extent immediately adjacent the roll 10. This stop is carried upon the end of a vertically extending rod 61 whose lower end is connected to a lever 62 fulcrumed to a standard 63 on the base 1 and having its opposite end extended in position to cooperate with a cam 64 on the shaft 26.

The mandrel 11 is preferably tubular and has a number of closely spaced, substantially radial passages 66 extending from its external surface into its cavity 67 whose outer end is closed by a plug 68 and whose inner end communicates through an axial passage 69 and radial passages 70 in the shaft 5, with a relatively fixed hollow collar 71 whose cavity in turn is connected to any suitable 85 exhausting device such as a suction pump or fan.

Under conditions of operation the driving pulley 7 is turned by power from a suitable source so that the shafts 5, 6 and 26 are continuously rotated, as are also the spindles 49 and 50 with their associated cutters. At the beginning of a cycle of operations the cams on the shaft 26 are so designed and arranged that the adhesive applying roller 42 is held out of engagement with the mandrel 11 by the action of the spring 73, the guiding member 29 is in such a position that its pressure rolls 31 are clear of said mandrel, or but lightly engaging the same, the cutters 51 and 52 are in their lower positions out of engagement with the mandrel, the stop 60 is raised above the table 28 and the lever 12 is in such a position that the upper roll 10 is spaced away from the mandrel 11. 105

The blanks employed in my machine are preferably strips of paper of predetermined length having a circular curvature, and one of these, after being placed upon the table 28 in the position indicated in Fig. 3, is fed between the rolls 10 and 11, just as the cam 25 so acts on the toggle lever 18 as to depress the lever 12 and move the upper one of said rolls toward the other. As a consequence, the strip is gripped and as it is drawn between the rolls, its end is directed downwardly around the roll or mandrel 11 by the sharp edge 30 of the strip guide 29, so that it passes between the latter and the pressure rolls 31. At the same time the air is exhausted from the interior of the mandrel 11 through the collar 71 so that this end of the strip is drawn and held in close engagement with the tapered surface of the roll and as it passes under the roller 42, this is depressed 115 into engagement with it, thereby applying to its external surface adhesive received from the gathering roll 41, for which purpose the cam 47 depresses the adjacent end of the lever 44 so as to swing the arms 43 120

125

130

in the required direction to bring said roll 42 into engagement with the strip on the mandrel.

- As the two coacting rolls 10 and 11 continue to turn, the strip is further drawn between them and is wound upon the lower one, its successive layers being pressed into the most intimate engagement with each other by the pressure rolls 31 so that the adhesive applied by the roller 42 is utilized to the best advantage. Just before the final complete layer of the strip is wound upon the mandrel, the cam 47 so far releases the lever 44 as to allow its adjacent end to rise, thus causing the roll 42 to move out of engagement with the tubular body on the mandrel or roll 11. As a consequence the external surface of the finished body α^1 has no paste applied to it.
- After the second end of the strip α has passed between the rolls 10 and 11, the cam 64 releases the lever 62 so as to permit the stop 60 to move down and into engagement with the top of the table 28, thus preventing another strip being fed into the rolls. The cam 57 now acts on the roller carried by the lever 48 to bring the two cutters 51 and 52 into positions in which they cooperate with the mandrel 11 to trim the ends of the tubular body thereon so that the edges of its convolutions are flush and lie in two parallel planes. These cutters remain in their operative positions, for one full revolution of the mandrel 11 after which the lever 48 is released by its cam 57 permitting them to move away from the body α^1 . At the same time the cam 25 releases the lever 12 and the cam 36 releases the strip guide 29 with its pressure rolls 31, so that the finished tube α^1 may be easily removed from the mandrel 11;—it being noted that previously to this the suction is cut off in any suitable manner from the collar 71 and from the interior of said mandrel.
- Thereafter the cam 64 acts upon the lever 62 to raise the stop 60 above the table 28, the lever 12 is again moved down so as to bring the upper roll 10 into cooperative position relatively to the mandrel 11 and the cam 36 acts upon the roller 35 to force the plunger 31 and with it the strip guide 29 toward said mandrel ready to act upon another paper strip α as above described.
- From the above description it will be understood that my machine not only holds and guides a curved strip or blank so that it may be wound into a frusto-conical body 2, but at the proper time applies adhesive so that the various convolutions of said strip are permanently connected. At the same time the pressure rolls are caused to act on the strip as it is being wound to press its successive layers into the most intimate contact and finally the ends of the finished tube or body are trimmed to parallelism.

The various parts are so disposed as to permit of the quick and convenient removal of the finished tube from its mandrel and likelihood of damage to the machine or marring of a partially finished body is prevented by the automatically acting stop which makes it impossible to feed a second strip into the machine while the previous strip is being wound.

It will be understood that the movement of the lever 12 is relatively slight so that the proper cooperation of the gears 8 and 9 is not interfered with. The same is true of the cutter-carrying lever 48 for the path of movement of its cutters is merely that necessary to insure their cutting through the three convolutions of strip material constituting the tube α^1 which is insufficient to interfere with the proper cooperation of the gears 54 and 55.

I claim:

1. The combination in a tube forming machine of a supporting structure; two coacting tapered rolls thereon; means for driving the rolls; a device for curving a strip around one of the rolls after it is fed between the same; and means for fastening together the overlying layers of the strip wound on said roll.

2. The combination in a tube forming machine of a supporting structure; two coacting tapered rolls thereon; means for driving the rolls; a device for curving a strip around one of the rolls after it is fed between it and the other roll; the same consisting of a guide adjacent the coating portions of the rolls, and means for bodily moving said device toward and from one of the rolls.

3. The combination in a tube winding machine of a pair of coacting tapered rolls; means for driving the rolls; a guide having an edge extending adjacent the coating portions of the rolls for directing a strip around one of the latter; and pressure rollers carried by said guide in engagement with said roll.

4. The combination in a tube winding machine of a pair of coacting tapered rolls; means for driving the rolls; a guide having an edge extending adjacent the coating portions of the rolls for directing a strip around one of them; pressure rollers carried by said guide in engagement with said roll; with a cam controlled mechanism for governing the position of said guide relative to the roll.

5. The combination in a tube winding machine of a pair of coacting tapered rolls; means for driving said rolls; means for directing around one of the rolls a sheet of paper fed between them; and means for automatically separating the rolls after the completion of the tube.

6. The combination in a tube winding machine, of a pair of driven shafts supporting a pair of coacting tapered rolls, means for

- directing around one of the rolls a sheet of paper fed between them for the formation of a tapered tube, and means for automatically shifting one of the shafts to separate the 5 rolls after completion of the tube.
7. The combination of a supporting structure; a pair of coacting tapered rolls; a lever fulcrumed to said structure and operative on one of the rolls to govern its position 10 relatively to the other roll; mechanism operative on the lever to move its roll toward and from the other roll; and means for directing a strip around one of the rolls after it has passed between it and the other roll.
- 15 8. The combination of a supporting structure; a pair of coacting tapered rolls; a lever fulcrumed to said structure and operative on one of the rolls to govern its position relatively to the other roll; mechanism 20 operative on the lever to move its roll toward and from the other roll; a device for directing a strip around one of the rolls after it has passed between it and the other roll; and means for temporarily moving said device away from its roll to permit of the 25 introduction of the strip.
9. The combination in a tube winding machine of two coacting rolls; means for causing a strip to be directed around one of the 30 rolls; means for causing the convolutions of said strip to be held together; and a device for trimming the ends of the finished tube consisting of a movable member, cutters carried by the member; and means for automatically moving the member with the cutters toward and from a tube to be trimmed.
- 35 10. The combination in a tube winding machine of a pair of coacting tapered rolls; means for causing a strip passing between the rolls to be wound on one of them; means for applying adhesive to the strip as it is wound on the roll to cause its convolutions to adhere; a lever; a pair of cutters mounted on the lever; and mechanism for periodically and automatically actuating the lever to cause the cutters carried thereby to trim the ends of a tube on the roll.
- 40 11. The combination in a tube winding machine of a pair of coacting rolls; means for directing a length of strip material around one of the rolls after it has been passed between said rolls; a cam shaft; means for driving the rolls and the cam shaft; a series of pressure rolls mounted to 45 coat with one of said first rolls; a structure carrying said pressure rolls; and a cam on the cam shaft for causing said structure with its rolls to be periodically moved into and out of coacting position.
12. The combination in a tube winding machine of a pair of coacting rolls; a cam shaft; a lever operative upon one of said rolls to vary its distance from the other roll; and a cam on the cam shaft for periodically turning the lever on its fulcrum to vary 50 the separation of the two rolls.
13. The combination in a tube winding machine of a pair of coacting rolls of which one has a series of passages opening on its surface and connected to an air exhausting device; a cam shaft; means for directing around one of the rolls a piece of strip material fed between said rolls; a cam on the cam shaft controlling said directing means; a device for applying adhesive to a strip; a second cam on the cam shaft for governing the operation of said latter device, cutters for trimming the ends of a tube on one of the rolls; and a third cam on the cam shaft for controlling the operation of said cutter. 55
14. The combination in a tube winding machine of a pair of coacting rolls of which one has a series of passages opening on its surface and connected to an air exhausting device; a cam shaft; means for directing around one of the rolls a piece of strip material fed between said rolls; a cam on the cam shaft controlling said directing means; a device for applying adhesive to a strip; a second cam on the cam shaft for governing 60 the operation of said device; cutters for trimming the ends of a tube; a third cam on the cam shaft for controlling the operation of said cutters; a device for moving one of the rolls into and out of position to cooperate with the other roll; and a fourth cam on the cam shaft for controlling the operation of said last device. 65
15. The combination in a tube winding machine of a pair of coacting rolls; means for guiding a strip of material around one of the rolls after it has been passed between said rolls; and a stop for preventing the introduction of a second sheet between the rolls until the finished tube has been removed from its supporting roll. 70
16. The combination in a tube winding machine of a pair of coacting tapered rolls; a table adjacent the line of coaction of the rolls; means for directing a strip of material fed from the table around one of the rolls; and an automatic stop operative adjacent the table for preventing the introduction of a second sheet until the tube has been removed from the roll on which it is 75 wound.

In witness whereof I affix my signature.
GEORGE H. WOMELSDORF.
